UNITED STATES PATENT OFFICE.

EUCLID I. LA CHAPELLE, OF BROCKTON, MASSACHUSETTS.

MACHINE FOR SEPARATING SHOES AND LASTS.

1,269,093.

Specification of Letters Patent. Patented June 11, 1918.

Application filed July 17, 1917. Serial No. 181,067.

To all whom it may concern:

Be it known that I, EUCLID I. LA CHAPELLE, a citizen of the United States, residing at Brockton, in the county of Plymouth and State of Massachusetts, have invented 5 a new and useful Improvement in Machines for Separating Shoes and Lasts, of which the following is a specification.

The last pulling operation (so-called) taking place during the process of manufacture, or after the completion of the shoes, is performed by hand and in the following manner:—The last, upon which the shoe has been lasted, being held in inverted position upon 10 a spindle, the workman places his right forearm upon the forepart of the shoe bottom, which is a bearing point for same while he separates, with both hands, the heel part of the shoe and the heel part of the last and 15 he so continues to bear more or less, according to his strength, upon the forepart of the shoe bottom and he also continues to hold the heel part of the shoe while moving the entire shoe longitudinally of the last to 20 finally separate the forepart of the shoe and the forepart of the last.

Shoes are often damaged at this operation, as this operation to be well performed, is firstly dependent upon the strength of the 25 workman and secondly upon his skill and being an arduous operation to perform by hand, it is always accompanied by uncertain results and is often defective, the heel lining being torn or still more serious damage often 30 results at the forepart of the shoe, as this operation places considerable strain on the vamp, at the instep and at the ball of the shoe, with the result that the vamp or the vamp-seam is often ripped and, moreover, 35 the breaking of the shank so-called often 40 takes place.

The damage to the upper or to its lining or to both at this time, is due to the fact that, at the time of the lasting operation, the 45 upper, the lining and the counter have been set very tightly to the lines of the last, as good lasting practice dictates, so that, the upper back of the ball of the last and notably, the throat part of the vamp or the corners of the quarters of Blucher style shoes are overstrained and are often torn apart 50 at the time of the separation of the shoe and

the last at the ball portion and the lining, over the counter, is often torn against the last when the heel part of the shoe and the 55 heel part of the last are being separated.

That objectionable feature of damage to 60 shoes at the last pulling operation applies to all kinds of shoes such as welts, McKays and turns.

The object of my invention is to provide 65 a machine which will overcome the objections noted and enable the operation of separating a last and a shoe mechanically, so that the operation may be made easier and so that 70 undue strain on the vamp and on the vamp-seam, as well as on the heel lining, may be overcome and thus liability of damage to 75 shoes, in the general run of the shoe factory, may be eliminated.

My invention provides means for compressing a shoe on a last to cause the upper to loosen on the last at the time of the separation of the shoe and the last, particularly 75 at the ball portion and also at the time of 80 the separation of the shoe and the last at the heel portion.

Considering that the bottom of a finished shoe, (of a welt shoe, for example) is resili- 85 ent and also considering the somewhat rounded transverse shape of the bottom plane surface of a last relatively to the sub-stantially flat surface of the sole of a shoe on the last, it is obvious that by moving the sole toward the last at or near its edge, or that by compressing the shoe bottom, or 90 the sole, against the last bottom, a certain amount of movement or resiliency will re-sult, which will cause the upper to loosen on the last, so that the shoe and the last will 95 then be separated without damage to the upper. The widest portion of a last being at the ball, it is the portion that offers most resistance and which tends both to strain the upper and the vamp-seam at the throat 95 of the vamp at the last pulling operation and I preferably compress the sole at the ball, or near the ball, but I do not, of course, limit myself to compressing at that partic- 100 ular point, as I may extend the sole compressing means to the full length and width of the largest shoe forepart likely to be set in the machine.

I will now explain the embodiment of

means shown in the accompanying drawings to accomplish the object stated, in which:—

Figure 1 is a side elevation, partly in section, of a foot power actuated machine embodying my invention for separating a last and a shoe.

Fig. 2 is a front elevation thereof.

Fig. 3 is a side elevation, illustrating a step in the operation.

10 Fig. 4 is a similar view, illustrating the use in connection with a last which is not hinged.

15 Fig. 5 is a cross sectional view of a shoe forepart illustrating the action of the sole compressing means.

Fig. 6 is a side elevation of the machine arranged to be driven by motive power.

Fig. 7 is a detailed view of a clutch mechanism, which is preferably employed.

20 As shown in the drawings, the table 1 is mounted on suitable supports and has a jack 2, mounted thereon in guideways 3 therein, arranged to slide toward and from the front of the table, a spring 4 being interposed between the jack and the table in position, when released, to move the jack to the rear end of the table. The jack has the usual pivoted last pin or spindle 5, whereby a shoe on a last and the last, may

25 be held and supported and whereby the shoe and the last may be separated at the toe-end and at the ball or entirely, when the jack 2, is moved from the front of the table 1, and with which a lug 6 is integrally formed, said last pin being yieldingly held in upright position by a spring 7, interposed between said lug 6 and a lug 8 on the jack. A pin 9 is provided, which is adapted to be inserted in the lugs 6 and 8 to lock the last

30 pin 5 in upright position, when a hinged last is used on the jack.

35 The spring 4 is not, however, absolutely necessary to this invention, after the shoe and the last have been separated at the ball by other means. When other means are used to pull the last off of the shoe at the ball, I may then, still use the spring 4 to finally pull the last out of the shoe, but when the last is pulled off at the ball and

40 finally out of the shoe, entirely by the said spring 4, as shown in Fig. 1, I then use a comparatively strong spring and I preferably employ means, such as the treadle 26, whereby the jack may be moved against the

45 action of said spring.

46 A cross-head 10 is mounted on a pair of vertically disposed, reciprocating side-rods 11, which are connected, at their lower ends, by a link 12, to a treadle 13, so that the cross-head may be drawn downward thereby, and springs 14 are arranged on said side rods, between the table and collars 25 on said rods, normally to hold said cross-head in raised position. A sole compressing

45 member 15 is pivotally suspended on the

under side of the cross-head to swing transversely thereof, and has its sole engaging portion, preferably, covered with rubber, extending longitudinally of the cross-head a distance corresponding to the width of 70 the widest portion of the sole of any shoe likely to be placed in the machine and it has also a longitudinally concave underside, conforming to the transverse curvature of the sole at its widest portion, which is at 75 the ball.

The said member 15, as shown in the drawings holds, at the ball portion, the shoe bottom toward the last and, to some extent, overcomes the straining of the vamp and of 80 the vamp-seam against the top of the last at the instep portion, when the heel portion of the shoe is lifted off the last by the operator and the said member 15 is also helpful in holding the shank portion of the bottom 85 of the shoe toward the last, to overcome the breaking of the shank by excessive upward movement thereof. I could, of course, extend the member 15, so that it would contact with and hold the sole at the shank portion, 90 after the heel of the shoe had been lifted off the last to a suitable extent.

The sole engaging means, 15, also serves to hold the shoe from movement against the strain of the last pulling operation, and 95 in view of holding the shoe firmly from movement at that time, I may engage the shoe in the shank, in the immediate vicinity of the ball portion or I may extend the sole engaging means, so as to engage and hold 100 the shoe at the ball portion and farther back, where the sole is narrower and slants downward below the bottom plane surface of the forepart of the shoe and the sole engaging means would then be preferably 105 wide enough to engage the extreme sole edge of the shoe.

A rest 16, of rigid material, is supported on the upper ends of a pair of vertical rods 17, reciprocally mounted in the table and having encircling springs 18 thereon interposed between the table and the underside of the rest 16 and normally acting to hold said rest in an elevated position, limited by the stop nuts 19, on the lower ends of said 110 rods. A pressing member 20 is pivotally mounted on the upper side of the rest 16, in position to tilt correspondingly with the sole compressing member 15 and the upper side or face of the member 20, is longitudinally concave and transversely convex to conform to the middle portion or front end of the instep portion of a shoe on a last. The shoe engaging portion of the member 20 is preferably covered with rubber 20', 115 and a pair of springs 21 are interposed between said member 20 and the rest 16 at each side of its pivot, so that, when it is tilted in either direction, from a middle position, one of said springs will tend to 120

125

return it to its middle position. An arm 22 is rigidly formed on the rest 16 and a screw 23 is mounted in one end of the cross-head 10, in position to engage said arm in a depressed position of the cross-head. A stop screw 24 is provided with the rest 16 in position to limit the downward movement thereof by engaging the table. A treadle 26 is connected to the jack 2 by a flexible connection 26', so arranged that when the treadle is depressed the jack will be drawn forwardly.

The manner in which the machine is employed to separate a last and a shoe, is as follows:—A hinged last, having a shoe thereon, (a welt shoe being herein shown) is placed on the last pin 5, as shown in Fig. 1, and the jack is then drawn forwardly by depressing the treadle 26, so that the forepart of the shoe extends between the members 15 and 20, preparatory to being grasped thereby, as indicated by the dotted position of Fig. 1. In this position, the portion of a shoe forepart adjacent the vamp-seam of the shoe, or the vamp-seam itself in most cases, rests directly on the lower member 20, engaging the upper at each side of the seam or engaging the seam itself. The treadle 13 is then depressed, causing the upper member 15 to be forced into engagement with the sole, so that downward pressure is applied thereto across its widest portion and, particularly to the portion adjacent its edge, as indicated in full lines in Fig. 5. Before the pressure is applied to the sole, the tension thereof causes the upper to be drawn tightly about the last, but when the pressure is applied to the sole, particularly at its edge or near its edge, the strain on the upper is then somewhat relieved, as indicated in Fig. 5. I want it well understood as being within the spirit of my invention to separate a shoe and a last during the releasing action of the compressing means upon the shoe or even after the disengagement of the compressing means and the shoe.

There are at least two distinct advantages in doing as above explained; the last being held from movement against the heel part of the shoe during the separation of the shoe and the last at the heel part and friction of the last bottom against the shoe bottom being also reduced during the separation of the shoe and the last at the forepart.

The downward pressure of the cross-head 10 causes the forepart of the last to be tilted with relation to the heel part, and preferably at the same time the operator may lift up the heel part of the shoe, so that it may be entirely freed from the last, as indicated in Fig. 3. The operator then releases the jack, permitting it to be moved rearwardly by spring 4, so that the last is thereby finally withdrawn from the shoe. The down-

ward movement of the cross-head causes also the bottom plane surface of the heel of the shoe to move, to some extent, away from the bottom plane surface of the heel of the last.

70

The stop screw 23, is very important, as it prevents the application of excessive pressure on the shoe by the member 20, through the action of the springs 18, as the sole of the shoe is being compressed by the member 15 and more especially, after the last has been separated from the shoe forepart, in view of overcoming the crushing of the shoe by the members 15 and 20. The limiting screw 23, engages the arm 22 on the rest 16, after the cross-head has been depressed to a certain extent, which is determined by adjustment of said screw.

75

The pressing member 20, which also acts as a support for the forepart of the shoe, is preferably employed, although it is not absolutely necessary to this invention, as a rigidly held last pin may support the entire last, as for example, when a last which is not hinged is used.

80

With a machine as herein shown, having the member 20, when a shoe is to be removed from a last which is not hinged, the pin 9 is then preferably removed, so that the last pin 5 may swing forward, as indicated in Fig. 4.

85

Instead of operating the machine by foot power, as above described, it may be operated by motive power driven means, as illustrated in Figs. 6 and 7. As therein shown, a constantly driven shaft 27 has a pulley 28 mounted thereon, and a clutch member 29 is splined on said shaft, arranged to be engaged with said shaft by a treadle mechanism 30, so as to cause said shaft to be rotated with the shaft. A pair of straps 31 and 32 are arranged to be wound on said pulley and the strap 31 is connected to the cross-head 10, in the same manner as is the link 12, before described, and the strap 32 is connected to the jack 2 in such a position that a pull thereon will act to draw the jack back from its forward position. In operating the machine as thus arranged, the jack is pulled forward by hand, or by a foot treadle 26, as before described, and then the treadle mechanism 30 is actuated, so that the clutch member 29 engages the shaft 28, which begins to wind the strap 31 first and the strap 32 thereafter. The relative length of the straps is such that the parts connected thereto will be drawn down nearly to the position of Fig. 3 before there is any pulling action on the strap 32, which is then brought into action to withdraw the last from the shoe, while the latter is compressed, as shown in Fig. 5. As soon as the last is thus freed from the shoe at the ball or farther back, the spring 4 will act to push the jack to its extreme rear position.

90

95

100

105

110

115

120

125

130

The word "separate", occurring in the specifications and in the claims, when the context so permits, applies to partly as well as to wholly separating the shoe and the 5 last.

This present invention covers the function of loosening the upper of a shoe on a last to better the longitudinal separation of the shoe and the last and also the separation of 10 the shoe and the last at the heel portion and, as far as I am aware, that function was never before performed by any machine, device, apparatus or implement. The adaptation of this principle to machines for separating a shoe and a last, is a distinct step in 15 the progress of the art and must be distinguished, because of its novelty, principle and importance, from a mere improvement or perfection of what has gone before. It is 20 a notable fact that a machine for separating a shoe and a last has not as yet been offered to the trade and the last pulling operation is still performed by hand.

It is not absolutely necessary to this invention to have the sole engaging means, 15, and the shoe upper engaging means, 20, mounted for swinging movement and the same is true of the last pin, 5.

It is to be noted that, although not of 30 prime importance to this invention, a novel feature resides in the sequence of movements of the sole compressing means 15 and of the shoe and last separating means 5.

In its most important and novel aspect, 35 however, this invention contemplates the provision of novel sole engaging means 15, so built and so arranged that for the first time in machines for separating a shoe and a last the sole of the shoe on the last has 40 been compressed, to cause looseness of the upper of the shoe on the last during the time of the separation of the shoe and the last, whether at the separation of the heel part, or of the forepart or of both.

45 The said novel sole engaging means 15, with additional means, such as the spindle 5, for example, constitute a patentable invention.

It is a novel and very important feature 50 of this invention to compress the sole of a shoe, during the time that the heel part of the shoe and of the last are being separated, as the upper and the counter of the shoe are thereby somewhat loosened on the last and 55 the operation of separating the heel of the shoe and of the last is thus made easier and reduces the liability of tearing the lining of the shoe against the heel of the last.

The shoe compressing means, 15 and 20, 60 for causing looseness of the shoe upper on the last, during the time that the shoe forepart, particularly the ball part, and the last are being separated, constitute a novel and most important feature of this invention.

65 The shoe compressing means, 15 and 20,

compressing the shoe during the time that the shoe and the last are being separated at the heel part, also constitute a novel and most important feature of this invention.

Additional novel features will be pointed 70 out in the appended claims.

I do not limit myself to the construction herein shown: suffice it to say, that I claim, as within the scope of my invention and of this patent, any machine, device, apparatus, 75 tool, implement or thing capable of accomplishing the object stated and embodying any claim or claims of this patent.

Having described my invention, what I claim as new and desire to secure by Letters 80 Patent of the United States is:—

1. A machine of the character described, having, movable shoe compressing means for loosening the upper of a shoe on a last, comprising sole engaging means and shoe 85 upper engaging means, and limiting means for limiting the relative movement of said sole engaging means and of said shoe upper engaging means.

2. A machine of the character described, 90 having, shoe compressing means, comprising movable sole engaging means for loosening the upper of a shoe on a last, and additional shoe engaging means to hold the shoe against the strain of said shoe compressing 95 means and limiting means for limiting the movement of said movable sole engaging means relatively to said additional shoe engaging means.

3. A machine of the character described, 100 having, sole compressing means, substantially as described, for loosening the upper of a shoe on a last and a spindle for engaging the last, said sole compressing means and said spindle being arranged for co-operation in separating the shoe and the last, during the time that the upper is loosened on the last by said sole compressing means.

4. A machine of the character described, 110 having, sole compressing means, substantially as described, for loosening firstly, the upper of a shoe on a last, a spindle for engaging the last, a movable support for said spindle and actuating means for moving secondly, said movable support and the last.

5. A machine of the character described, having, sole compressing means, for loosening the upper of a shoe on a last, a movable spindle for engaging the last and limiting 120 means for limiting the movement of said movable spindle toward said sole compressing means, during the time that the upper is loosened on the last by said sole compressing means.

6. A machine for separating a shoe and a last, having, movable sole compressing means, for loosening the upper of the shoe on the last, additional movable last engaging means positioned at the heel of the last 125

and moving means for moving said additional movable last engaging means relatively to the movement of said movable sole compressing means.

5 7. A machine for separating a shoe and a last, having, sole compressing means 15, for loosening the upper of the shoe on the last, preparatory to the separation of the shoe and the last and additional coöperating 10 means for engaging the last at the heel portion.

8. A machine for separating a shoe and a last, having, sole engaging means, so built and so arranged that the sole of the shoe on 15 the last may thereby be compressed, at or near its edge, to cause looseness of the upper of the shoe on the last, during the time of the separation of the shoe and the last and additional coöperating means for engaging the last at the heel portion.

9. A machine for separating a shoe and a last, having, sole compressing means, for loosening the upper of the shoe on the last, shoe and last separating means and actuating 25 means for said shoe and last separating means, arranged to actuate said shoe and last separating means after the upper of the shoe has been loosened on the last by said sole compressing means, for the purposes 30 described.

10. A machine of the character described, having, sole compressing means, substantially as described, for loosening firstly, the upper of a shoe on a last, last engaging 35 means, a movable support for said last engaging means and actuating means for actuating secondly, said movable support, during the time that the upper is loosened on the last by said sole compressing means.

40 11. A machine of the character described, having, shoe compressing means, for loosening the upper of a shoe on a last, last engaging means, a movable support for said last engaging means, a single actuating 45 means for actuating said shoe compressing means and said movable support and connections between said shoe compressing means and said single actuating means and connections between said movable support 50 and said single actuating means.

12. A machine of the character described, having, sole compressing means, for loosening the upper of a shoe on a last, and actuating means for said sole compressing 55 means, comprising a clutch and connections, located relatively to said sole compressing means and to said clutch.

13. A machine of the character described, having, shoe compressing means, for loosening the upper of a shoe on a last, during the time of the separation of the shoe and the last, shoe and last separating means, positioned at the heel part of the last, a single actuating means for all said means, connections positioned relatively to said shoe

compressing means and to said single actuating means and connections positioned relatively to said shoe and last separating means and to said single actuating means, said connections being relatively timed so 70 that said shoe compressing means may be actuated prior to the actuation of said shoe and last separating means.

14. A machine of the character described, having, sole compressing means, for loosening firstly, the upper of a shoe on a last, 75 movable last engaging means, yielding means for said movable last engaging means and stopping means for stopping the action of said yielding means.

15. A machine of the character described, having, sole compressing means for loosening the upper of a shoe on a last, last holding means, positioned at the heel part of the last, a movable support for said last holding 85 means and a single actuating means for said sole compressing means and for said movable support.

16. A machine of the character described, having, sole compressing means for loosening the upper of a shoe on a last, last holding 90 means, positioned at the heel of the last, a movable support for said last holding means, actuating means for actuating firstly, said sole compressing means and additional actuating means, for moving secondly, said movable support and the last out of the shoe.

17. A machine of the character described, having, movable sole compressing means 100 for loosening the upper of a shoe on a last and means for returning said movable sole compressing means to normal position after its compressing movement upon the shoe.

18. A machine of the character described, having, sole compressing means for loosening the upper of a shoe on a last, actuating 105 means for said sole compressing means and means for returning said sole compressing means to normal position after its actuation by said actuating means.

19. A machine of the character described, having, sole engaging means for loosening the upper of a shoe on a last, and shoe upper engaging means, a spindle for engaging 115 the last, a movable support for said spindle and actuating means for said movable support.

20. A machine of the character described, having, movable sole compressing means 120 for loosening the upper of a shoe on a last, and arranged for movement against the shoe on the last and limiting means, for limiting the movement of said movable sole compressing means against the shoe.

21. A machine of the character described, having, sole compressing means, substantially as described, means for separating a shoe and a last and actuating means for said means, timed to operate relatively to 130

- said sole compressing means, so that said means for separating a shoe and a last will be thereby actuated at a predetermined time.
22. A machine of the character described, having, sole compressing means for loosening the upper of a shoe on a last, during the time of the separation of the shoe and the last, a spindle for holding the last during the time of the compression of said sole compressing means upon the shoe, and additional means for separating the shoe and the last longitudinally.
23. A machine of the character described, having, sole compressing means 15, and shoe upper engaging means 20, all said means being positioned at the forepart of a shoe on a last, for loosening the upper of a shoe on a last, during the time of the separation of the shoe and the last.
24. A machine of the character described, having, sole compressing means for loosening firstly, the upper of a shoe on the forepart of a last and means for longitudinally separating secondly, the shoe and the last, during the time that the upper is loosened on the last by said sole compressing means.
25. A machine of the character described, having, the elements recited in claim 24 and moving means for moving firstly, said sole compressing means and moving means for moving secondly, said means for separating the shoe and the last.
26. A machine of the character described, having, sole compressing means for loosening the upper of a shoe on the forepart of a last, movable last engaging means and moving means, under the control of the operator, for moving said movable last engaging means and the last out of the shoe, during the time that the upper is loosened on the forepart of the last by said sole compressing means.
27. A machine of the character described, having, sole compressing means for loosening the upper of a shoe on the forepart of a last and last engaging means, arranged to engage the last independently of the shoe upper, for holding the last and the shoe relatively to said sole compressing means and arranged for longitudinally separating the shoe and the last.
28. A machine of the character described, having, the elements recited in claim 27 and springs for supporting said sole compressing means.
29. A machine of the character described, having, the elements recited in claim 27 and a spring for supporting said last engaging means.
30. A machine of the character described, having, sole compressing means for loosening firstly, the upper of a shoe on a last, movable last engaging means, arranged to engage the last independently of the shoe upper and arranged to separate the last and the shoe and actuating means for said movable last engaging means, comprising a clutch and connections positioned relatively to said movable last engaging means and to said clutch for separating secondly, the shoe and the last.
31. A machine of the character described, having, sole compressing means arranged for positively loosening the upper of a shoe on a last, and last engaging means, arranged to engage the last independently of the shoe upper and arranged to support the last and the shoe, during the time of the compression of said sole compressing means upon the shoe and during the time that the shoe and the last are being separated at the heel portion.
32. A machine of the character described, having, movable shoe compressing means, for loosening the upper of a shoe on a last, during the time of the separation of the shoe and the last, movable last engaging means, arranged to engage the last independently of the shoe upper and arranged to separate the shoe and the last, a single actuating means for said movable shoe compressing means and for said movable last engaging means, moving means for moving said movable last engaging means relatively to said movable shoe compressing means, in one direction of its movement, and additional moving means for moving said movable last engaging means relatively to said movable shoe compressing means, in the opposite direction of its movement.
33. A machine of the character described, having, shoe compressing means 15, for loosening the upper of a shoe on a last, during the time of the separation of the shoe and the last, movable shoe engaging means 20, to support the shoe relatively to said shoe compressing means and springs 18, to move said movable shoe engaging means and the shoe thereby engaged toward said shoe compressing means.
34. A machine for separating a shoe and a last, having, sole compressing means for loosening the upper of the shoe on the last, and shoe and last separating means for longitudinally separating the shoe and the last.
35. A machine of the character described, having, movable shoe compressing means for loosening the upper of a shoe on a last, during the time of the separation of the shoe and the last and limiting means for limiting the movement of said movable shoe compressing means against the shoe, after the complete separation of the forepart of the shoe and the last, to overcome over-compression upon the shoe by said movable shoe compressing means.
36. A machine of the character described, having, shoe compressing means, comprising sole engaging means 15, and upper engaging means 20, and a spindle 5, to hold

a last and a shoe relatively to said sole engaging means and to said upper engaging means.

37. A machine of the character described, having, shoe and last separating means, positioned at the heel part of a shoe on a last for longitudinally separating the shoe and the last and shoe engaging means, so built and so arranged that the sole of the shoe on the last may be thereby compressed, for causing looseness of the upper of the shoe on the last, during the time that the shoe and the last are being separated by said shoe and last separating means.

38. A machine of the character described, having, shoe compressing means, for loosening firstly, the upper of a shoe on a last, last holding means and a support for said last holding means, arranged for movement relatively to said shoe compressing means, so that the last may be thereby moved out of the shoe, during the time that the upper is loosened on the last by said shoe compressing means.

39. A machine of the character described, having, movable sole compressing means, for loosening the upper of a shoe on a last, last engaging means, a movable support for said last engaging means, moving means for moving said movable sole compressing means and additional moving means for moving said movable support.

40. A machine for separating a shoe and a last, having, movable shoe and last separating means for loosening the upper of the shoe on the last, sole compressing means and actuating means for actuating said sole compressing means independently of said movable shoe and last separating means.

41. A machine for separating a shoe and a last, having, sole compressing means for loosening the upper of the shoe on the last, and additional movable coöperating last engaging means, positioned at the heel of the last, and actuating means for actuating said sole compressing means independently of said additional movable coöperating means.

42. A machine for separating a shoe and a last, having, movable sole compressing means for loosening the upper of the shoe on the last, actuating means for said movable sole compressing means and adjusting means to predetermine the amount of movement of said movable sole compressing means toward the shoe for overcoming the crushing of the shoe thereby after the longitudinal separation of the shoe and the last.

43. A machine of the character described, having, movable sole compressing means, actuating means for said movable sole compressing means, connections between said movable sole compressing means and said actuating means, for actuating said movable sole compressing means toward the shoe for

loosening the upper of the shoe on the last and movable last holding means, positioned at the heel part of the last.

44. A machine for separating a shoe and a last, having, sole compressing means for loosening the upper of the shoe on the last, last holding means, positioned at the heel part of the last and actuating means for said sole compressing means, said actuating means being so arranged that the sole of the shoe on the last may be thereby positively compressed to cause looseness of the upper of the shoe on the last, for the purposes described.

45. A machine of the character described, having, movable sole compressing means for loosening the upper of a shoe on a last, movable coöperating shoe engaging means, positioned at the forepart of the shoe, for holding the last and the shoe against the strain of said sole compressing means and a spring for returning said movable coöperating shoe engaging means to normal position after the termination of its operation.

46. A machine of the character described, having, the elements recited in claim 45 and means for returning said movable sole compressing means to normal position after the termination of its operation.

47. A machine for separating a shoe and a last, having, sole compressing means, arranged for movement with the shoe under compression of said sole compressing means, movable holding means for holding the last and the shoe against the strain of the compression of said sole compressing means, and shoe and last separating means, positioned at the heel part of the last, for separating the shoe and the last.

48. A machine of the character described, having, movable sole compressing means for loosening the upper of a shoe on a last, movable shoe and last separating means, actuating means for said movable sole compressing means and moving means for said movable shoe and last separating means.

49. A machine of the character described, having, movable sole compressing means, and movable shoe and last separating means, said movable sole compressing means and said movable shoe and last separating means being arranged for independent movement to permit sequence of movement of said movable means.

50. A machine of the character described, having, movable sole compressing means for loosening the upper of a shoe on a last and a movable spindle for separating a shoe and a last, said means being arranged for independent movement to permit sequence of movement of said movable sole compressing means and of said movable spindle.

51. A machine for separating a shoe and a last, having, movable sole compressing means for loosening the upper of the shoe

- on the last, a movable spindle for separating the last and the shoe and actuating means timed for simultaneously actuating said movable sole compressing means and said 5 movable spindle.
52. A machine for separating a shoe and a last, having, movable sole compressing means for loosening the upper of the shoe on the last, movable shoe and last separating 10 means and actuating means timed for simultaneously actuating said movable sole compressing means and said movable shoe and last separating means.
53. A machine for separating a shoe and a last, having, shoe and last separating means, positioned at the heel part of the last, and sole compressing means for loosening the upper of the shoe on the last and for holding the shoe from movement against 15 the strain of the last pulling movement by said shoe and last separating means, substantially as described.
54. A machine for separating a shoe and a last, having, sole compressing means and a suitable support for said sole compressing 20 means for bringing about positive actuation of said sole compressing means upon the shoe for causing looseness of the upper of the shoe on the last and means, positioned at the heel of the last, for holding the shoe and the last relatively to said sole compressing means, for the purposes described.
55. A machine for separating a shoe and a last, having, sole compressing means for loosening the upper of the shoe on the last and means for separating the shoe and the last and timing mechanism for controlling the relative actuation of all said means.
56. A machine for separating a shoe and a last, having, movable means for loosening the upper of the shoe on the last and additional movable coöperating means for longitudinally separating the shoe and the last, the first mentioned movable means being arranged for movement in a substantially vertical direction relatively to said additional movable coöperating means.
57. A machine for separating a shoe and a last, having, sole compressing means for loosening the upper of the shoe on the last, actuating means for said sole compressing means, arranged for control by the foot of the operator and means for longitudinally separating the shoe and the last during the time that the upper is loosened on the last by said sole compressing means and actuating means for said means for longitudinally separating the shoe and the last.
58. A machine for separating a shoe and a last, having, movable sole compressing means for loosening the upper of the shoe on the last, yielding means for said movable sole compressing means and shoe and last separating means for separating the shoe 65 and the last.
59. A machine for separating a shoe and a last, having, movable sole compressing means for loosening the upper of the shoe on the last and additional movable means, positioned at the heel of the last, for engaging 70 the last and for separating the shoe and the last, all said movable means being arranged for independent movement.
60. A machine for separating a shoe and a last, having, sole engaging means for loosening the upper of the shoe on the last, last engaging means, positioned at the heel of the last, and means for holding said last engaging means with the last, yieldingly relative to said sole engaging means.
61. A machine for separating a shoe and a last, having, sole compressing means for loosening the upper of the shoe on the last, movable last engaging means, positioned at the heel of the last and means, positioned 85 relatively to said movable last engaging means for moving said movable last engaging means with the last relatively to said sole compressing means.
62. A machine for separating a shoe and a last, having, movable sole compressing means for loosening the upper of the shoe on the last, last engaging means, positioned at the heel of the last, actuating means for said movable sole compressing means, arranged to be operated by the operator's foot and means for returning said movable sole compressing means to normal operative position after its sole compressing movement.
63. A machine for separating a shoe and a last, having, two members, positioned at the forepart of the shoe on the last, for compressing the sole of the shoe on the last to loosen the upper of the shoe on the last, one of said members being arranged for movement toward the other of said members and means, positioned relatively to said members for permitting predetermination of the amount of compression to be applied to the shoe by said members.
64. A machine for separating a shoe and a last, having, two members, positioned at the forepart of the shoe for loosening the upper of the shoe on the last, one of said members being arranged for movement toward the other of said members and means, positioned relatively to said movable member for returning said movable member to normal operative position.
65. A machine for separating a shoe and a last, having, last engaging means, positioned at the heel of the last, for holding the last and the shoe thereon and sole compressing means for loosening the upper of the shoe on the last and means, positioned relatively to said sole compressing means for permitting predetermination of the amount of compression to be applied to the shoe by said sole compressing means for overcoming thereby

- over compression upon the shoe by said sole compressing means.
66. A machine for separating a shoe and a last, having, movable last engaging means, positioned at the heel of the last, for moving the last out of the shoe and coöperating sole compressing means for loosening the upper of the shoe on the last during the last moving action of said movable last engaging means.
67. A machine for separating a shoe and a last, having, sole compressing means for loosening the upper of the shoe on the last and last engaging means, positioned at the heel of the last and arranged for a variety of movements for properly holding the last relatively to said sole compressing means and for moving the last out of the shoe.
68. A machine for separating a shoe and a last, having, sole compressing means, arranged for a variety of movements for properly engaging the shoe and for loosening the upper of the shoe on the last and last engaging means, positioned at the heel of the last for moving the last out of the shoe.
69. A machine for separating a shoe and a last, having, sole compressing means for loosening the upper of the shoe on the last, actuating means for said sole compressing means and means, positioned relatively to said sole compressing means, for limiting the actuation of said actuating means.
70. A machine for separating a shoe and a last, having, movable sole compressing means for loosening the upper of the shoe on the last and a plurality of limiting means, positioned relatively to said movable sole compressing means, for limiting the operative movement of said movable sole compressing means at predetermined times.
71. A machine for separating a shoe and a last, having, sole compressing means for loosening the upper of the shoe on the last, last holding means, positioned at the fore-part of the last, and additional last holding means, positioned at the heel of the last, said sole compressing means and all said last holding means being arranged for coöperation.
72. A machine for separating a shoe and a last, having, movable sole compressing means for loosening the upper of the shoe on the last, last holding means, arranged for coöperation with said movable sole compressing means during the time of the separation of the shoe and the last and means for returning said movable sole compressing means to operative position after its sole compressing action upon the shoe.
73. A machine for separating a shoe and a last, having, movable sole compressing means and non-movable means, positioned relatively to said movable sole compressing means, for guiding said movable sole compressing means to cause positive loosening of the upper of the shoe on the last by said movable sole compressing means and last holding means, arranged for coöperation with said movable sole compressing means during the time of the separation of the shoe and the last.
74. A machine for separating a shoe and a last, having, sole compressing means for loosening the upper of the shoe on the last and coöperating last engaging means, positioned at the heel of the last, and means for bringing about positive compression of the sole to cause looseness of the upper of the shoe on the last by said sole compressing means to better the longitudinal separation of the shoe and the last.
75. A machine for separating a shoe and a last, having, sole compressing means for loosening the upper of the shoe on the last and coöperating shoe and last separating means, positioned at the heel of the last, for separating the shoe and the last longitudinally during the time that the upper is loosened on the last by said sole compressing means.
76. A machine for separating a shoe and a last, having, last supporting means, positioned at the heel of the last, sole compressing means for loosening the upper of the shoe on the last, said last supporting means and said sole compressing means being relatively positioned, so as to permit the separation of the heel of the shoe and the heel of the last during the upper loosening action of said sole compressing means and last supporting means, positioned at the fore-part of the last for supporting the last against the strain of the compression of said sole compressing means upon the shoe.
77. A machine for separating a shoe and a last, having, last engaging means, positioned at the heel of the last and movable sole compressing means for loosening the upper of the shoe on the last and limiting means, positioned relatively to said movable sole compressing means and arranged for movement therewith for limiting the amount of compression upon the shoe by said movable sole compressing means.
78. A machine for separating a shoe and a last, having, last engaging means, positioned at the heel of the last, and movable sole compressing means for loosening the upper of the shoe on the last and limiting means, positioned relatively to said movable sole compressing means for limiting the movement of said movable sole compressing means toward the shoe.
79. A machine for separating a shoe and a last, having, movable sole compressing means for loosening the upper of the shoe on the last and movable last holding means, positioned at the heel of the last, all said means being arranged for coöperation during the time of the loosening of the upper.

on the last by said movable sole compressing means.

80. A machine for separating a shoe and a last, having, movable sole compressing means arranged to positively loosen the upper of the shoe on the last prior to the start of the separation of the shoe and the last, last holding means, positioned at the heel of the last, and means for positively moving said movable sole compressing means.

81. A machine for separating a shoe and a last, having, movable sole compressing means, arranged to positively compress the sole of the shoe on the last to better the longitudinal separation of the shoe and the last, last holding means, positioned at the heel of the last, and means for positively moving said movable sole compressing means.

82. A machine for separating a shoe and a last, having, a single movable shoe engaging means for loosening the upper of the shoe on the last and a single movable last engaging means, positioned at the heel of the last and arranged for coöperation with said single movable shoe engaging means.

83. A machine for separating a shoe and a last, having, movable means for engaging the sole of the shoe and coöperating movable means for engaging the upper of the shoe for compressing the shoe to loosen the upper on the last, limiting means for limiting the relative movement of said movable means and additional limiting means for determining the extent of movement of all said movable means.

84. A machine for separating a shoe and a last, having, movable shoe engaging means, arranged to engage the sole of the shoe only and arranged to positively compress the sole of the shoe against the last to loosen the upper of the shoe on the last, actuating means for said movable shoe engaging means, so arranged that said movable shoe engaging means may be thereby positively actuated and last holding means, positioned at the heel of the last.

85. A machine for separating a shoe and a last, having, sole compressing means and actuating means therefor, arranged to positively actuate said sole compressing means to positively compress the sole of the shoe on the last and shoe and last separating means, positioned at the heel of the last.

86. A machine for separating a shoe and a last, having, sole engaging means, positioned at the forepart of the shoe on the last and arranged to positively compress the sole of the shoe on the last, coöperating shoe upper engaging means, positioned at the forepart of the shoe on the last and shoe and last separating means, positioned at the heel of the last.

87. A machine for separating a shoe and a last, having, means for loosening the up-

per of the shoe on the last prior to the start of the separation of the shoe and the last and coöperating last engaging means, positioned at the heel of the last.

88. A machine for separating a shoe and a last, having, means for loosening the forepart of the upper of the shoe on the forepart of the last prior to and during the time of the longitudinal separation of the shoe and the last and coöperating last engaging means, positioned at the heel of the last.

89. A machine for separating a shoe and a last, having, means for loosening the forepart of the upper of the shoe on the forepart of the last, to better the longitudinal separation of the shoe and the last and shoe and last separating means, positioned at the heel of the last.

90. A machine for separating a shoe and a last, having, last holding means, positioned at the heel of the last, sole compressing means for loosening the upper of the shoe on the last and actuating means for said sole compressing means, arranged to cause said sole compressing means to maintain uniform upper loosening action during the separation of the shoe and the last at the heel part and during the separation of the shoe and the last at the forepart.

91. A machine for separating a shoe and a last, having, last holding means, positioned at the heel of the last, and sole compressing means for loosening the upper of the shoe on the last during the longitudinal separation of the shoe and the last and arranged to hold the shoe against the strain incident to the longitudinal separation of the shoe and the last.

92. A machine for separating a shoe and a last, having, last holding means, positioned at the heel of the last and sole compressing means, arranged to positively compress the sole of the shoe on the last during the separation of the shoe and the last.

93. A machine for separating a shoe and a last, having, last holding means, positioned at the heel of the last, and sole compressing means, arranged to engage the sole of the shoe at or near the ball line for loosening the upper of the shoe of the last to better the longitudinal separation of the shoe and the last.

94. A machine for separating a shoe and a last, having sole compressing means for loosening the upper of the shoe on the last to better the separation of the shoe and the last and arranged to overcompress the shoe on the last during the separation of the shoe and the last at the heel part, to hold the last from movement within the shoe, and arranged to release its overcompressing action upon the shoe, to permit movement of the last within the shoe at the separation of the shoe and the last at the fore-

part and shoe and last separating means, positioned at the heel of the last and arranged to move the last from within the shoe.

- 5 95. A machine for separating a shoe and a last, having, sole compressing means for loosening the upper of the shoe on the last to better the separation of the shoe and the last and shoe and last separating means, positioned at the heel of the last and arranged to separate the shoe and the last during the time of the releasing action of said sole compressing means upon the shoe.
- 10 96. A machine for separating a shoe and a last, having, sole compressing means for loosening the upper of the shoe on the last to better the separation of the shoe and the last and shoe and last separating means, positioned at the heel of the last and arranged to separate the shoe and the last after the start of the releasing action of said sole compressing means upon the shoe.

- 15 97. A machine for separating a shoe and a last, having, sole compressing means for loosening the upper of the shoe on the last to better the separation of the shoe and the last and shoe and last separating means, positioned at the heel of the last and arranged to separate the shoe and the last after the start of the releasing action of said sole compressing means upon the shoe.
- 20 98. A machine for separating a shoe and a last, having, sole compressing means for loosening the upper of the shoe on the last to better the separation of the shoe and the last and shoe and last separating means, positioned at the heel of the last and arranged to move the last from within the shoe.
- 25 99. A machine for separating a shoe and a last, having, sole compressing means and actuating means for said sole compressing means, mounted for non-yielding action in forcing said sole compressing means against the shoe to positively compress the sole of the shoe on the last.

positioned at the heel of the last and arranged to separate the shoe and the last after the disengagement of said sole compressing means and the shoe.

98. A machine for separating a shoe and a last, having last holding means, positioned at the heel of the last and sole compressing means for loosening the upper of the shoe on the last and constructed and arranged to engage and compress the marginal side portions of the sole, substantially on the arc of a circle, to loosen the upper of the shoe on the last.

99. A machine for separating a shoe and a last, having, sole compressing means and actuating means for said sole compressing means, mounted for non-yielding action in forcing said sole compressing means against the shoe to positively compress the sole of the shoe on the last.

In testimony whereof, I have signed my name to this specification, in the presence of a subscribing witness.

EUCLID I. LA CHAPELLE.

Witness:

H. B. DAVIS.
